(57) **CLAIM**

The ornamental design for a eye compress, as shown and described.

DESCRIPTION

FIG. 1 is a perspective view of an eye compress, shown in an environment of use, shown with the nose element in an extended configuration;

FIG. 2 is a front elevational view of FIG. 1;

FIG. 3 is a front elevational view thereof, shown in a flat position of use;

FIG. 4 is a rear elevational view of FIG. 3;

FIG. 5 is a left-side elevational view of FIG. 3;

FIG. 6 is a right-side elevational view of FIG. 3;

FIG. 7 is a top plan view of FIG. 3; and,

FIG. 8 is a bottom plan view of FIG. 3.

The broken lines showing a person in FIG. 1 depict environmental matter and form no part of the claimed design. The remaining broken lines represent stitching, and are part of the claimed design.
